UNITED STATES PATENT OFFICE.

MELVILLE CLARK, OF CHICAGO, ILLINOIS.

VARIATION-INDICATOR FOR AUTOMATIC MUSICAL INSTRUMENTS.

No. 830,302.

Specification of Letters Patent.

Patented Sept. 4, 1906.

Application filed July 18, 1903. Serial No. 165,245.

To all whom it may concern:

Be it known that I, MELVILLE CLARK, a citizen of the United States, residing at Chicago, in the county of Cook and State of Illinois, have invented new and useful Improvements in Variation-Indicators for Automatic Musical Instruments, of which the following is a specification, reference being had to the accompanying drawings, forming a part thereof.

The purpose of this invention is to provide a simple means by which the operator upon an automatic musical instrument or mechanical player may be guided in his operation of the parts under his control for regulating the speed and intensity of the playing.

It consists in the features of construction set out in the claim.

In the drawings, Figure 1 is a front elevation of a portion of a piano-player embodying my invention, portions of the case being broken away to disclose the interior structure. Fig. 2 is a section at the line 2 2 on Fig. 1. Fig. 3 is a detail top plan view with a portion of the case broken away. Fig. 4 comprises plan views of corresponding portions of two perforated sheets with indication-lines at different positions relative to the perforations. Fig. 5 is a similar plan of a portion of such a sheet having a modified form of indication-marks. Fig. 6 is a similar view showing a further modification in respect to the indication-marks.

In the drawings there are shown the customary and familiar parts of an automatic player for keyed instruments, commonly called a "piano-player," comprising the two rolls 1 and 2 for carrying the perforated sheet 3, which is wound upon them, the casing 4, which incloses the mechanism by which the rolls are operated mechanically, and the mechanism by which pneumatic action which is controlled by the perforated sheet is produced. I have shown in the drawings a portion of the motor for actuating the rolls having a rock-shaft 5, provided with an index-finger 6, oscillating in front of a graduated segment-dial 7, which is customarily present in certain types of players, the rock-shaft being connected with the mechanism for driving the rolls 1 and 2, its connection being such that the rocking of the shaft to carry the index-finger back and forth over the dial operates governing devices for controlling the speed of the motor, and thereby regulating the tempo or rate of performance of the music.

Since the particular motor mechanism forms no part of my invention, it is not illustrated in detail, but only shown in general features as comprising a train (represented by wheels 8 8^a 8^b 8^c) for driving the chucks 9 9, in which the rolls 1 and 2 are held, and having a governor 10, which is regulated by means of the rock-shaft 5, as described. At the forward side of the player, within the case, there is mounted a horizontal rod or bar 11, on which there is a traveler 12, which has a finger 13 projecting up through a slot in the casing 4 in front of the winding-roll 1. This finger may be terminated by a button 13^a, as illustrated in Figs. 1 and 2, and it may have an extension 13^b above the position at which the button is shown, and which extension when present may be projected up over the roll 1 and be extended rearward to overhang the perforated sheet and terminate directly above the tracker-range 14. To the rock-shaft 5 there is secured a lever-arm 15, which operates against an abutment 16, projecting from the traveler 12, so that as the rock-shaft 5 is rocked by the handle 17, attached to it for that purpose, the rocking movement by which the index-finger 6 is carried over to the right will push the indicator-finger 13 to the left. A spring 19 is connected to the traveler 12 to retract it, and thus the rocking of the shaft in the opposite direction will permit said indicator-finger to return to the right.

On the perforated sheet 3 there is imprinted in one form of my invention illustrated in Fig. 3 a serpentine or zigzag line 18, the course of which to the right or left of an imaginary line parallel with the lateral edge of the paper midway in the zone or limited portion of said width within which the serpentine or zigzag line lies is intended to indicate the speed at which the music should be played at the various points in the length of the perforated roll corresponding to the different points in that zigzag line. The operator will control the speed by rocking the shaft 5 by means of its handle 17, and by so governing his operation of said handle as to keep the indicator-finger 13 in position right or left in its slot, corresponding to the point of the zigzag line which is over the tracker-range, he will be able to regulate the speed with nicety, according to the intention of the arranger of the perforated sheet, who, it will be understood, delineates the zigzag line with intention to indicate the speed of the various parts of the music in this manner.

The rod or bar 11 may be extended to the left beyond the range necessary to carry the traveler 12 for the purpose of carrying another traveler 20. The extended portion of the bar is denoted 11^a, and it will be understood that it is not necessarily integral with the bar 11. The traveler 20 is similar to the traveler 12 and corresponds to a zigzag or sinuous line 21 on the perforated roll 3, (see Fig. 1,) its lateral deflections or sinuosities being confined to a limited zone or longitudinal strip at the left-hand portion of the perforated roll, over or opposite which the terminal finger 22 or button 23 of the traveler 20 may oscillate within the range of a slot in the casing through which the traveler 20 protrudes. A light spring 24, connected to the traveler 20, tends to hold it at the left-hand limit of its oscillation. A light cord or cable 25 is attached to the traveler 20 and extends about guide-pulleys 26 26 26 26 to the fluctuating side 29 of the bellows 28, which operates the pneumatic devices for causing the playing action of the instrument. It will be understood that in such an instrument or player the force of the stroke by which the keys are actuated and the consequent intensity or loudness of the tone produced varies according to the degree of exhaustion or evacuation of the bellows, and the bellows being held normally expanded by a spring and the exhaustion of air therefrom operating to compress the spring according to the degree of exhaustion and consequent collapse of the bellows the greater such collapse the louder the tone produced, and the connections described, from the moving wall of the bellows to the traveler 20, it will be observed, are such that at the position of greatest inflation—that is, at the normal position of rest of the fluctuating wall of the bellows—the finger or button of the traveler will stand at the extreme left-hand end of the slot and opposite or overhanging the left-hand margin of the paper and that at the position of greatest exhaustion of the bellows said finger will stand at the right-hand limit of its slot and of what may be called the "expression zone" of the controlling-sheet—that is, the longitudinal strip or portion of the area of said sheet within which the sinuous or zigzag or expression line 21 is contained. The operator controlling the intensity of tone by the rapidity with which he operates the bellows' pedals may govern the expression correctly according to the expression-line by so pumping as to keep the indicator-finger at all times coinciding with such line at the point thereof at which it crosses the tracker-range. It will be manifest that without departing from the substance of the invention the extension terminal fingers 13^b and 22 of the travelers which pertain to the tempo and expression indicators, respectively, being omitted, the tempo and expression lines on

the perforated sheet may be so placed with respect to the sound-controlling perforations that any given point on the tempo or expression line immediately opposite the tempo or expression button will correspond to the transverse line in the sheet which is at the same time on the tracker-range, so that the operator may keep the button directly on the tempo or expression line—that is, registered with the point in the line which is passing the tracker-range. It would not be possible to discover in any given instance merely by the eye whether the expression-line were applied so as to be read, so to speak, at the tracker-range or so as to be read at the bottom; but for the purpose of illustrating the two modes I have shown in Fig. 4 a short section of the perforated sheet duplicated, one representation having the line in one position and the other in the other.

Instead of the zigzag or sinuous lines there may be employed for indicating the proper expression and tempo at different parts in the length of the controlling-sheet in each instance—that is, for both expression and speed indication—a series of parallel lines extending longitudinally on the sheet, whose distance inward from the margin or from any selected base-line may correspond to the different degrees of speed and intensity, respectively. Thus, for example, in Fig. 5 there are shown at the right-hand side of the controlling-sheet lines marked with the customary words for denoting different speeds from slowest to fastest—to wit, "Andante, Moderato, Allegro, Adagio, Presto"—and at the left-hand side of the sheet a series of lines marked with the customary words indicating degrees of intensity or loudness—to wit, commencing at the left nearest the margin of the sheet, "Piano, Pianissimo, Forte, Fortissimo." At points in the length of the controlling-sheet at which the tempo or expression corresponding to any one of these lines should be observed a character—as a star or a cross-mark—is placed upon such line to indicate that the indicator-finger should be on the line thus marked at the point thus marked and should stay on that line until some other indication is given. At any point at which the speed or expression should change a mark may be placed upon the line trending obliquely toward the line corresponding to the tempo or expression to which the change should be made, and on such other line at the point at which the tempo or expression indicated by that line should be attained there is placed a star or cross-line. The operator will thus be able without the zigzag line to understand at what point the indicator-finger should be kept in order to obtain the correct tempo and expression. There may with advantage also be placed in the margin of the sheet the words which may be considered the names of the several lines indicating the

speed or expression in the common musical terms above quoted, or their abbreviations, as follows: For expression, "P, PP, F, FF" and for speed, "A, D, Mod., Al., Ad., Pr," as seen on Figs. 4, 5, and 6. Another quite convenient mode of marking the controlling-sheet to afford guidance to the operator in respect to expression and speed is represented in Fig. 6, wherein the parallel lines above described are broken or interrupted at the point at which the expression should change. When the change is abrupt, as from one speed to another, the line indicating the prior speed terminates and the line indicating the speed to which the change is made commences at the same transverse line. When the change is gradual for the effect of acceleration or retard, a longitudinal interval would intervene between the termination of one line and the commencement of the other. In this form of marking it is convenient also to apply the customary words or characters denoting the different speeds and intensities either at the termination or break in the line or opposite that point in the margin. In these different forms of applying the lines to the controlling-sheet to guide the operator in respect to expression and speed the star or other mark on the parallel lines, the word or sign either on the lines or in the margin, or the mere abrupt terminations and commencements of the lines, respectively, constitute "indications" of speed and expression, and I do not limit myself to any one of these specifically, though I prefer to employ the interrupted lines last above described with marginal words or abbreviations corresponding to the various speeds and expressions denoted by the lines, placing such marginal markings opposite the breaks in the lines as above described.

I claim—

1. In an automatic musical instrument or player, in combination with the traveling controlling-sheet, a motor for actuating it independent of the means controlled by the sheet for playing the instrument; a horizontal bar extending transversely with respect to the travel of the sheet at the forward side; a traveler mounted on such bar having an indicator-finger extending up in front of the sheet in proximity thereto; a rock-shaft by which the speed of the motor is regulated at will; a lever-arm on said rock-shaft, and link connections from said lever-arm to the traveler to oscillate the latter as the shaft is rocked.
2. In an automatic musical instrument or player having a controlling-sheet for the playing devices, a source of energy directed by such sheet for controlling the playing; an indicator mounted for oscillation transversely with respect to the travel of the sheet in proximity thereto, and connections from said source of energy for oscillating the indicator as the degree of energy varies, the controlling-sheet having expression indications disposed

at positions varying laterally within a longitudinal strip or zone of said sheet corresponding in width to the range of oscillation of the indicator.

3. In an automatic musical instrument or player having a traveling controlling-sheet for governing the playing devices, a source of energy which is directed by said sheet for controlling the playing, and a motor for actuating the traveling sheet independent of the said source of energy controlled by the sheet; an indicator mounted for oscillation transversely with respect to the travel of the sheet in proximity thereto, and connections from said source of energy for oscillating said indicator as the degree of energy varies, the sheet having expression indications disposed at positions varying laterally within a longitudinal strip or zone of the sheet corresponding in width to the range of oscillation of the indicator.

4. An automatic musical instrument or player having a controlling-sheet and pneumatically - operated playing devices controlled thereby; an air-chamber from which said pneumatic devices are operated; an indicator mounted for oscillation transversely with respect to the travel of the controlling-sheet directly in front of the latter, and connections from said air-chamber for oscillating the indicator as the air tension in said chamber varies.

5. In an automatic musical instrument or player having a traveling controlling-sheet for governing the playing devices, an exhaust-bellows by which said devices are operated; an indicator mounted for oscillation transversely with respect to the travel of the sheet in proximity thereto, and connections from the moving wall of the exhaust-bellows for oscillating the indicator, the controlling-sheet having expression indications disposed at positions varying laterally within a longitudinal strip or zone of the sheet corresponding in width to the range of oscillation of the indicator.

6. In an automatic musical instrument or player having a controlling-sheet for governing the playing devices, a bellows by which the playing devices are operated; an indicator mounted for oscillation transversely with respect to the travel of the sheet in proximity thereto, and connections from the bellows for oscillating the indicator, the sheet having expression indications disposed at positions varying laterally within a longitudinal strip or zone of the sheet corresponding in width to the range of oscillation of the indicator.

7. In an automatic musical instrument or player having a controlling-sheet for the playing devices, a source of energy directed by such sheet for controlling the playing; an indicator mounted for oscillation transversely with respect to the travel of the sheet in prox-

imity thereto, and connections from such source of energy for oscillating the indicator as the degree of energy varies, the controlling-sheet having a plurality of parallel longitudinal lines disposed at lateral intervals within a longitudinal strip or zone of said sheet corresponding in position and width to the position and range of oscillation of the indicator.

8. In mechanical piano-players and organs, the operative combination of the actuating force or exhaust-bellows, the music-roll or tune - sheet, the ordinary expression - line thereon, and an indicator suitably connected to the movable leaf or side of said bellows, said indicator being positioned near to and intermediate of the width of the music-roll or tune-sheet, and moving by reason of said connection to and movement of the movable leaf as described, thereby indicating the degree of

pressure or exhaust acquired and required and being capable of use in the manner and for the purpose described.

9. In mechanical piano-players and organs, the combination with the actuating mechanism and the tune-sheet provided with the expression-line described and shown, of an index connected to the said actuating mechanism and caused, by reason of such connection, to move and traverse in front of the music-roll or tune-sheet in the manner and for the purpose described.

In testimony whereof I have hereunto set my hand, in the presence of two witnesses, at Chicago, Illinois, this 1st day of July, 1903.

MELVILLE CLARK.

In presence of—

FRED G. FISCHER,
M. GERTRUDE ADY.
